Primary Examiner—Antoine Duval Davis**[57] CLAIM**

The ornamental design for an anti-freeze recycling unit, as shown and described.

DESCRIPTION

FIG. 1 is a perspective view of an anti-freeze recycling unit showing my new design;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof; and,

FIG. 7 is a bottom plan view thereof.

The broken line showing of wheel assemblies and hoses are for illustrative purposes only and forms no part of the claimed design.
